TYPE COMPOSING AND CASTING MACHINE

Byrd S. Fine, Clinton, Mass., assignor to The Colonial Press, Inc., Clinton, Mass., a corporation of Massachusetts

Application October 22, 1938, Serial No. 236,403

10 Claims. (Cl. 199—30)

This invention relates to a type composing and casting machine, and more particularly to safety control mechanism which prevents improper operation of such a machine under certain circumstances.

5 Type composing, setting and casting machines of the type sold under the trade-marks "Linotype" and "Intertype", comprise mechanism for successively assembling matrices and tapered 10 spacers or space bands on an assembling elevator to form a line of approximate required length and then transferring the assembled matrices by means of elevator and delivery mechanism to a position where the spacers are moved 15 to justify the line to full length, and molten type metal is cast into the characters thereon to form a slug or line of type. Such a machine may be operated both manually and automatically by a standard keyboard controlled by a pattern or 20 record tape which is fed through a record reader mechanism, known under the trade-mark "Teletypesetter", which is arranged and connected to cause the selection of required matrices in accordance with the record.

25 Machines of this general type are complicated in structure and delicate in their operation, and improper operation sometimes occurs either automatically or through human error, such as improper manipulation of the keyboard or a mis- 30 take in the tape record. If such error results in a line of matrices not being full enough for the spacer blanks to justify the line to full width, then molten type metal may escape from the machine during the casting step and perhaps 35 seriously injure the operator and damage the matrices. Likewise, if the last matrix of the line is not positioned properly on the assembling elevator, then it may fall out and leave the line unfilled or it may jam the operating mechanism 40 when the elevator tries to go up and so cause trouble and a considerable amount of time loss. Safety devices have been provided to overcome a part of the difficulties that may be met, as shown in the patents to Walden No. 2,006,848 45 and Goetz et al. No. 2,006,860 of July 2, 1935. Applicant's invention relates to machines of the type set forth in said patents and provides further safety mechanisms in addition to those therein disclosed.

50 One object of this invention is, therefore, to improve an integral line type casting machine of the class described, by providing safety mechanism so constructed and arranged as to prevent full movement of the elevator and subsequent casting of the type, if for any reason the line of 55

matrices is too short or loose for justifying in the casting mechanism, and which causes the composing mechanism to stop and remain inoperative until the error has been corrected by an attendant and a releasable power connection has been re-set manually for further operation of the machine.

A further object is to provide a type casting machine of the class described with a device which will automatically place the last matrix 10 in proper position and permit the elevator to operate and move the assembled matrices to a type casting position, if the line is adequately full.

A still further object is to provide a fully automatic type composing and casting machine with control mechanism which insures that the line of matrices is adequately full before the elevator starts on its upward movement and that the last matrix is properly positioned before the elevator 15 mechanism can transfer the assembled matrices to the delivery slide trackway for the casting step, and which cooperates with other safety mechanism to insure that the machine stops and prevents accidents due to improper assembling 20 of the matrices. Further objects will be apparent 25 in the following disclosure.

Referring to the drawings, which illustrate one embodiment of this invention satisfying all of the above objects, and in which like reference numerals indicate like parts:

Fig. 1 is a fragmentary front elevation of an automatic type setting machine of the class illustrated in said prior patents;

Fig. 2 is a section on the line 2—2 of Fig. 1; 35

Fig. 3 is a fragmentary perspective view of the elevator operating mechanism looking in the direction of the arrow 3 of Fig. 1;

Fig. 4 is a side elevation of the elevator control handle in a normal operating position;

Fig. 5 is a similar view showing the parts in an abnormal position which prevents further operation of the elevator;

Fig. 6 is a fragmentary plan view of the elevator and matrix feeding mechanism, looking in 45 the direction of the arrow 6 in Fig. 1;

Fig. 7 is a fragmentary elevation, partly in section, taken on the line 7—7 of Fig. 6, which shows the matrix assembling members; and

Fig. 8 is a similar view showing how the last 50 matrix is positively forced into position.

This invention applies particularly to a power operated integral line type casting machine as shown in said patents, which comprises a keyboard operated either manually or automatically 55

for successively releasing matrices from a supply magazine at the top of the machine. These matrices fall onto a traveling belt and are assembled with spacers on the spaced bars of an 5 assembling elevator, after which the elevator delivers the accumulated line of matrices to a delivery slide trackway and further mechanism arranged for casting the molten type metal into the characters thereon, and finally the matrices and spacers are sorted and selectively returned to 10 their magazines for re-use in the machine. This selection and assembling of the matrices may be caused by automatic operation of the keyboard mechanism controlled by a pattern, such as a 15 perforated tape record. In accordance with the disclosure in said prior patents, the record tape determines the automatic operation of the machine whereby the premade record governs the selection of the matrices and causes the elevator 20 to be operated, as predetermined by the operator who punched the tape. When the perforations on the tape call for lifting the elevator, a clutch controlled cam rotates the elevator operating shaft; but if the elevator cannot move, for any 25 reason, a releasable connection between the cam and shaft, which comprises a manually operable handle, breaks apart and prevents further movement of the record tape until the defect has been corrected by an attendant.

30 One aspect of my invention involves providing such a machine with mechanism which locks the elevator against movement until the correct number of matrices has been assembled thereon. This lock is preferably released by movement of the 35 slide bar to a position which insures that the line of matrices is adequately full. Then if, and when, the releasable connection is made between the cam and elevator shaft, the elevator will operate to transfer the matrices to mechanism arranged for casting the line of type. A second 40 feature involves a pusher operated automatically, and preferably in timed relation with the elevator movement, which insures that the last matrix in the line is pushed into place and locked in 45 position before the assembled matrices are delivered for the casting step. This is preferably accomplished by a spring pressed pusher which is normally held inoperative by the elevator and released for operation when the elevator starts 50 upwards.

55 Referring now more particularly to the drawings, I have shown these protective mechanisms in association with a device of the type set forth in said patents, and to which reference is to be had for further description of the machine. The machine comprises a slide 10 and an elevator 11 having two spaced bottom rails to which matrices 12 are delivered by means of a belt 13. The matrices slide from the belt down a slide 60 block 14 between side plates 15 and are delivered in a substantially vertical position onto the top of the elevator rails. The slide bar 10 is movably mounted on the roller 16 and a slide bracket 18, and it carries at its left hand end a vertically 65 projecting offset finger 20 located between the elevator rails. The first matrix is assembled against this finger, and as succeeding matrices are put into place, the slide bar is automatically moved towards the left. A positively rotated star 70 wheel 22, which rotates counterclockwise, serves to thrust the matrices successively into position on the elevator rails.

75 The matrices are assembled between two spaced side rails 24 (Fig. 6) and form the top portion of the elevator; and they are carried on a frame

26 supported for vertical sliding movement, as is well understood. The elevator is moved vertically at stated intervals by means of a positively rotated shaft 28 which connects through a rock arm 29 thereon with a link 30 pivotally 5 attached to the bottom of the elevator. This elevator moves vertically when the line of matrices and spacer blocks 32 supplied from another source, have been assembled in position to make an adequately full line. Thereafter, the 10 assembled matrices are transferred by the elevator to a delivery slide trackway (not shown) and delivered to the casting mechanism for making the integral type bar.

The slide bar 10 is moved to the left under 15 the propelling effort of the star wheel 22 against the pull of a coiled spring 35 (Fig. 1) connected to the bar by a tape 36. The bar is prevented from returning towards the right by a brake mechanism comprising a swinging arm 37 having 20 two spaced brake blocks 38 engaging the top and bottom of the slide bar 10. The frictional grip of the brake blocks prevents the slide bar from moving to the right further than permitted by a set screw 40 in a bell crank lever 42 pivoted 25 at 43 and having a weighted arm 44. A spring 45 tends to hold the brake arm 37 towards the right against the force of the weighted arm 44. An adjustable sliding dog 48 is suitably mounted 30 on the slide bar and secured in an adjusted position by a set screw 49, and its movement towards the left is limited by the stop 51. A hand release lever 52 pivoted on the stud 53 serves to 35 release the brake and allow return movement of the slide bar after the elevator has removed the 35 matrices therefrom. The top of the elevator is also arranged to strike one end of lever 54 pivoted at 55, and the right hand end of this lever pushes the brake release lever when the elevator goes up and thus sets the slide 10 for a further 40 loading operation.

The elevator mechanism may be operated by hand or by power. An automatic device controlled by a perforated record tape or pattern may be of the well known type sold under the 45 trade-mark "Teletypesetter", and reference may be had to said patents for a description of the parts pertinent to the present invention. As shown in Figs. 3, 4 and 5, such a construction comprises a manually operable handle 56 connected to actuate the elevator rock shaft 28. The power driving mechanism comprises a driven gear wheel 58 adapted to be connected through a 50 slideable clutch member 59 with a shaft 60 which carries thereon an elevator cam 62 arranged to strike a roller 63 on the right hand end of an arm 64 freely pivotally mounted on the shaft 28. The left hand end of the swinging arm 64 is shaped as a cam 65 having its lower portion of 55 shorter radius than the upper part relative to the pivot of the arm 64, and this cam is engaged by a plunger 66 slidably mounted in the handle 56 and held against the cam by a compressed spring 67. The frictional pressure of this plunger tends to hold the freely swinging lever 64 in a certain forced relationship relative to the handle 56, so that when the elevator cam 62 is revolved to lift the right hand end of the lever 64, the handle 56 will normally go down and the shaft 28 will be turned counterclockwise and thus operate the elevator through the arm 29 and link 30 as described.

Also, freely mounted on the same shaft 28 is a further swinging arm or lever 70 which has a finger 71 at its outer end arranged to control 75

the rotation of the record reading shaft 72. This shaft is likewise driven positively by a gear 73 through a slidable clutch member 74. The shaft 72 operates the mechanism which moves the record tape and associated parts. This tape carries certain perforations which operate the mechanism of the prior patents and serve to connect the clutch 59 and cause rotation of the elevator cam 62 and elevation of the shaft 60.

10 The clutch 74 is slidably operated by mechanism comprising a link 76 connected to the lower end 78 of a bell crank pivoted on a rock shaft 79 and which has an upstanding arm 80 adapted to serve as a clutch throw out member. This arm 80 has a hole therein with a cam surface adapted to engage the beveled cam surface 62 of a lug mounted on the rotating clutch member 74. The clutch throw out member 80 may be held in engagement with the clutch by means of the 15 latch arm 84 which is pivoted on a stud 85 and held in a forward locking position by a spring 86. That is, when the tape is to be stopped while the elevator operates, the end of the latch 84 lies in back of the top of the clutch throw out arm 20 80 and thus holds the lug 82 in the opening of the throw out arm 80 against the pressure of spring 88 and keeps the clutch disconnected. The spring 88 normally holds the clutch connected, so that the record reading shaft rotates 25 continuously during the period of loading the matrices onto the slide bar.

The rocking arm 84, which is pivotally mounted on the stud 85, has a depending arm 90 located beneath and in the path of movement of the end 71 of the rock arm 70, so that when the elevator is started in its movement by the elevator cam 62, the arm 90 lifts and allows the spring 86 to pull the latch 84 into position behind the clutch throw out member 80. Then, 30 when the clutch operating lug 82 comes around in its next revolution, it slips into the cam opening in the arm 80 and thus disconnects the clutch and stops the record reading shaft and holds the tape stationary during the period that the elevator is going up and until the mechanism has been re-set for assembling another set of matrices. The arm 70 carries a set screw 96 therein which engages the top surface of the rock arm 64 so that it normally travels therewith. At the 35 other end of the arm 70 are one or more openings or recesses 94 (Fig. 5) so located as to engage a spring pressed plunger 95 (Fig. 3) mounted in the handle 56. A further opening 97 is so located in the rock arm 70 as to engage this plunger when the parts are in the disconnected 40 positions of Fig. 5.

This handle mechanism is so constructed, as explained in the prior patents, that when the elevator is incapable of moving vertically, although the tape has attempted to operate it through the elevator cam, the shaft 28 will remain stationary and the cam will thrust the arms 64 and 70 into the positions shown in Fig. 5, as permitted by the plunger 66 and the spring 45 pressed plunger 95. Hence, the elevator cam may operate without breaking any of the mechanism and the machine will thereafter come to stop until the obstruction has been removed. This is brought about by the fact that the end 71 of the 50 rock lever 70 remains up in the air and permits the latch 84 to be drawn down into a locking position, so that the clutch 74 is disconnected and thus stops the tape and all other mechanism associated therewith.

55 The elevator cam is adapted to be revolved

just once and then held stationary until a new line of matrices has been assembled. That is, the sliding clutch member 59 is held normally out of connection with the driving gear 58 because the clutch operating arm 100, similar to 5 the arm 80 above described, is held in engagement with a cam lug, similar to lug 82, which rests within an opening 102 in the arm 100. This arm 100 is pivotally mounted on a rock shaft 104 and may be adjusted in position between the 10 U-shaped arms 105 to which is attached a spring 106 tending to swing the clutch operating arm 100 towards the left and permit the clutch to be connected by the spring 108. A latch 110, similar to latch 84, and pivotally mounted on 15 the rock shaft 111, normally lies in back of the swinging arm 100 and holds the clutch parts disconnected.

After assembly of the line of matrices, which term is herein used to apply also to the spacers 20 32, mechanism described in the prior patents serves to rock that latch 110 out of engagement with the operating member 100 and permit the clutch to be thrown. This mechanism comprises an arm 114 having a cam 115 thereon adapted to 25 engage the lower end of the rocking arm 110 and thus lift it out of its locking engagement. The position of the cam 115 on the arm 114 is controlled by an arm 116 which is controlled by the delivery slide arm, so that the elevator mechanism cannot be actuated unless the delivery 30 slide arm has returned to a proper position indicating that the elevator is free to receive a new line of matrices. The other end of link 114 is connected to a latch bar 118 adapted to be moved 35 towards the right until it is in position to butt against the right hand end of a lug 121 on the rocking latch 122, which tends to be lifted by a spring 123. When this latch 122 is in that position, the arm 118 is so located that the cam 115 40 holds the latch 110 out of engagement with the clutch controlled arm 100 and permits the clutch to be connected by spring 108 and to revolve the elevator operating shaft 60 and cam 62 and thus move the elevator. As this takes place, a cam 45 130 on the elevator shaft 60 travels around and strikes the upper end of the latch 122 and thrusts it down and so releases the lug 120 on the latch 118, and other mechanism serves to draw that latch and the cam 115 back and allow the latch 50 110 to fall down in a locking position. When the cam 132 on the shaft 60 has revolved to a position where it engages a roller 134 on the rocking member 105 which carries the arm 100, it thrusts latch 100 forward into the path of the 55 lug on the clutch and thus serves to disconnect the clutch and stop the operation of the elevator.

The primary purpose of my invention is to provide safety mechanism, which insures that the 60 last matrix is assembled in the line on the elevator, and which also serves to hold the elevator locked until the right number of matrices and spacers have been put into position for justifying prior to the casting step, so that even if the 65 tape attempts to start movement of the elevator, this will result merely in the breaking of the releasable connection in the power mechanism, and stopping the tape and associated parts, and so preventing further movement of the elevator shaft until the releasable power connection 70 has been re-set manually. As shown in Figs. 1 and 6, the elevator rails 24 have vertical guide plates 140 which engage the sides of the matrices. These plates 140 terminate in swinging 75

plates 142 pivotally mounted at 143 thereon, and the ends of these swinging plates 142 have inwardly projecting lugs 148 which serve as latches to engage the side faces of the matrices and prevent them from falling back out of the assembled line. Flat springs 147 serve to keep the swinging plates 142 in a closed position. If, however, the last matrix, as may be the case, is not thrust past these locking lugs 148 and remains in the position shown in Fig. 7, then when the elevator goes up, that last matrix may fall laterally and perhaps jam the mechanism and stop the elevator, thus causing loss of time and possible damage to the matrix. Or, this matrix may fall clear and permit the elevator to travel upward with an incomplete line and thus cause the casting of a line with an error. Or if the missing matrix has made the line too loose, the line may not cast at all, thus causing several words to be left out of the matter to be printed. Or, if a line that is not adequately full should be cast, then molten metal would squirt between the matrices and spacers and cause possible damage to both, and a considerable amount of time will definitely be lost in getting the matrices out of the machine and cleaning them up for further use. I have provided a lock which keeps the elevator from starting up if the line of matrices and spacers is not adequately full.

The safety device which prevents upward movement of the elevator is shown particularly in Fig. 1. As there illustrated, a bar 150 suspended on a link 152 from the stud 53 has an upstanding member 154 adjustably secured thereon as by a set screw 155 slidably adjustable in an elongated slot 156 in the bar. The top of the member 154 lies in the path of the movable dog 48 on the slide rails 10. The other end of the bar 150 is pivotally connected to a rocking lever 160 pivoted at 161 on the framework of the machine. The lower end of this lever has a projection 162 which engages and lies in the path of movement of a shelf 164 on the elevator 26. A spring 165 tends to hold the parts in that locking position. Any tendency for the elevator to move upwardly is, therefore, taken as a direct thrust on the pin 161 and the elevator cannot move until the dog 48 has thrust the member 154 towards the left to a sufficient extent to unlock the end 162 from contact with the elevator. The dog and the arm 154 are, of course, properly adjusted so that this unlocking action will not take place until the last matrix required has been fed to the slide bar.

Assuming that the last matrix has fallen back into the position shown in Fig. 7 and that the star wheel is unable to thrust it past the locking lugs 148, I provide mechanism operated in timed relationship with movement of the elevator which will thrust that last matrix into position as it travels upwardly. In the preferred construction, this comprises an arm 170 pivoted on a stud 172 on a frame of the machine (Figs. 7 and 8) and the upper end 174 of the arm 170 is so shaped and arranged that it will pass over the star wheel and strike the last matrix 12 as it is being moved upwards by the elevator and so thrust it past the locking lug 148 and into proper assembled position. A spring 176 serves to move the lever arm 170 forward when permitted by movement of the elevator. That is, a projecting flange or the bottom 178 of the elevator engages an adjustable set screw 180 in the end of a lever 182 pivoted at 184 on the frame of the machine, and the right hand end 186 of this lever is adapted to engage the lower end 188 of the lever 170.

This arrangement is such that when the elevator is in its lowermost position, while the matrices are being assembled, the end 186 of the lever 182 serves as a lock to prevent the spring 186 from thrusting the pusher 174 into the line of assembly of the matrices. This pusher 174 is normally beneath the block 14 and out of the path of the assembling matrices. But as soon as the elevator starts on its upward path, the strong spring 176 immediately thrusts the pusher forward and makes sure that the last matrix is properly positioned. The pusher passes through a slot in the block 14 and so strikes the matrix substantially in its central vertical line. The length of the projecting end 174 of the arm and the strength of the spring 176 are such that the last matrix must go into position on the assembling elevator as soon as the arm is freed for movement; and this operation takes place automatically and does not require action on the part of the machine operator.

The operation of the mechanism has been set forth above. In normal usage of the machine as operated by the tape control mechanism, the characters on the tape cause the proper matrices and spacers to fall and be assembled on the slide bar, and as soon as the line has been filled, the latch 110 is moved by the cam 115 to release the clutch lock and cause the elevator shaft 60 to make a single complete revolution and cause the cam 62 to turn the shaft 28 and move the elevator upwards. This elevator cannot move, however, until the slide bar 10 has been forced towards the left far enough to unlock the latch 162; and if the tape causes the elevator cam 62 to operate, it will merely cause a yielding of the releasable connection in the handle locking mechanism, so that the shaft 28 will not have to turn. This thrusts the handle mechanism into the position of Fig. 5 and the tape and associated mechanism cannot operate again until the released connection in the handle has been manually re-set to its operative position. This is accomplished by the operator grasping the left hand end of lever 70 (Fig. 5) and lifting it relative to the handle 56, as permitted by the spring pressed plunger 95 and which holds the parts in their new positions during normal operation of the machine. The elevator remains locked in position until the right number of matrices and spacers have been put into place. Hence, any error in the fullness of the line made by an operator of the tape perforating machine cannot serve to cause trouble in the type composing and casting machine. Also, this mechanism insures that the last matrix will be thrust into position as the elevator goes up so that the type casting operation will be performed properly, provided the line is adequately full.

It will be appreciated that many modifications may be made in these safety mechanisms and that they may be applied to various types of machines other than those set forth in the prior patents above referred to, and that the drawings and description are to be considered in an illustrative and not in any limiting sense except as required by the scope of the copending claims.

I claim:

1. A type composing and casting machine comprising mechanism for selectively assembling matrices in a line, an elevator for receiving the assembled matrices which has spring pressed locking lugs for holding the last assembled matrix in position, mechanism for moving the elevator, and means operated in timed relationship with

the elevator movement which pushes the last matrix into position behind said locking lugs.

2. A type composing and casting machine comprising a slide bar and an elevator, means for

5 selectively assembling matrices thereon, a spring actuated pusher arranged to engage the last matrix and push it into position, and a locking device preventing movement of the pusher which is released by movement of the elevator, whereby

10 the pusher operates as the elevator rises.

3. A type composing and casting machine comprising mechanism for selectively assembling matrices on a slide bar, elevator mechanism for removing the assembled matrices as a unit from 15 the slide bar, means preventing movement of the elevator until a predetermined number of matrices have been assembled in position and means operated in timed relationship with the elevator movement which insures that the last 20 matrix is properly positioned when removed by the elevator.

4. A type composing and casting machine comprising a slide bar, mechanism for selectively assembling matrices on and moving the slide bar, 25 elevator mechanism including spaced rails for removing the matrices from said bar, automatically actuated power mechanism for moving the elevator, means for pushing the last matrix into position on the elevator, a locking device normally preventing movement of the elevator, 30 means for releasing said locking device which is actuated by movement of the slide bar to a predetermined position, and power driving mechanism including a releasable connection for actuating the elevator normally which causes said connection to be broken if the elevator is held by the lock.

5. A type composing and casting machine comprising mechanism including a slide bar for selectively assembling matrices thereon, means for pushing the matrices onto the slide bar and moving the latter therewith, an elevator having spaced rails and end locking lugs for receiving the assembled matrices and removing them from the 45 slide bar, a locking device for preventing movement of the elevator, means for releasing the locking device when the slide bar has been moved to a predetermined position, and means rendered operative by movement of the elevator for pushing the last matrix into position on the elevator rails as the elevator rises.

6. A type composing and casting machine comprising an elevator and a slide bar, means including a record tape for automatically and selectively assembling matrices on the elevator and slide bar, said elevator having spaced rails and means thereon for holding the assembled matrices and removing them from the slide bar, power mechanism including a releasable connection for actuating the elevator in accordance with the record on the tape, a locking device preventing movement of the elevator irrespective of the tape record, means for releasing the elevator lock when the matrices have been assembled on

the bar to form a predetermined length of line, and means independent of the assembling mechanism for forcing the last matrix into position on the elevator.

7. A type casting machine comprising a slide bar, mechanism for selectively assembling matrices thereon, an elevator for removing the matrices from the slide bar, power mechanism including a releasable connection for operating the elevator, a lock for preventing movement of the elevator 10 irrespective of the action of the power mechanism, means for releasing the lock when the matrices have been assembled in a predetermined length of line, and means rendered operative by movement of the elevator for forcing the last 15 matrix into position thereon.

8. A type composing and casting machine comprising automatically operated power mechanism controlled by a record tape for selectively assembling matrices in a line, an elevator for removing 20 the assembled matrices, a releasable lock for preventing movement of the elevator, means for releasing the lock when sufficient matrices have been assembled to make a full line, and power mechanism, including a releasable connection, 25 for operating the elevator automatically as required by the premade tape record, which causes the type assembling and elevator operating mechanisms to stop when the power mechanism attempts to move the elevator while held by the 30 lock.

9. A type composing and casting machine comprising power mechanism controlled by a record tape for selectively assembling matrices on an elevator and slide bar, automatically actuated 35 means controlled by said tape for moving the elevator in accordance with the tape record, a releasable locking device, which prevents movement of the elevator, means including an adjustable dog on the slide bar which releases the locking 40 device when sufficient matrices have been assembled to form a full line of predetermined but variable length, means including a releasable connection associated with the power mechanism which permits the elevator mechanism to be 45 operated normally as required by the record but causes said releasable connection to stop the associated type assembling and elevator operating mechanisms when the elevator movement is prevented by the locking device and means whereby 50 the releasable connection may be re-set for further operation of the machine.

10. A type composing and casting machine comprising a slide bar, mechanism for selectively assembling matrices on the bar, an elevator having spaced rails and means for holding the assembled matrices thereon, mechanism for moving the elevator, means for serially pushing the matrices onto said rails and mechanism operated in timed relationship with the elevator movement 60 which pushes the last matrix into position on the rails.

BYRD S. FINE.
